A. H. CHALMERS,
METHOD OF REPAIRING COKE OVEN WALLS,
APPLICATION FILED MAY 1, 1916.

UNITED STATES PATENT OFFICE.

ALBERT H. CHALMERS, OF FAIRFIELD, ALABAMA.

METHOD OF REPAIRING COKE-OVEN WALLS.

1,244,467.

Specification of Letters Patent. Patented Oct. 30, 1917.

Application filed May 1, 1916. Serial No. 94,647.

To all whom it may concern:

Be it known that I, ALBERT H. CHALMERS, a citizen of the United States, and resident of Fairfield, in the county of Jefferson and State of Alabama, have invented certain new and useful Improvements in Methods of Repairing Coke-Oven Walls, of which the following is a specification.

My invention relates to the art of maintaining by-product coke oven walls and has particular reference to a novel method for use in connection therewith.

After certain periods of operation, coke oven walls disintegrate so that they require repairs. Often local conditions in the combustion chambers bring about a fusion of the brick walls which make a replacement of brick imperative. Walls at times are pushed out of alignment, either by expanding of coal, explosions in combustion chambers or by careless operation of the pusher so that entire oven walls must be rebuilt the full length of the oven. In all these cases repairs to coke oven walls are a difficult undertaking, and if not properly done, often result in the total loss of the respective oven.

The method heretofore in vogue consisted in supporting the roof of the oven by wooden or iron beams, placed in holes cut through the oven walls near the roof and held in place by studding erected on the floor of the ovens along the walls of the adjacent combustion chamber. This method required that the oven about to be repaired had to be cooled down so that men could work inside the oven for a considerable period at a time, and so that the wooden supports would not dry out and catch fire from the heat of the adjacent flues. Such cooling down requires often from five to ten days if care has to be taken to prevent shrinkage cracks occurring in the brick work about to be repaired, as well as that of the adjacent combustion chambers. This studding, usually of the dimension 6x6 inches, would not permit the workmen proper access to their work, as the ovens are only 18 inches wide at best, allowing but 12 inches space in which the workman was forced to lay brick. After partial completion, the studs must be removed and the supports of the roof work cut off and taken out and the open spaces filled in. During the removal of the studding, parts of the walls remain unsupported and will not permit of filling the open spaces without leaving large joints in the brick work.

In many cases such supporting requires the splitting of shapes with the additional joints necessary to close up the opening.

Repairs to the oven floors cannot be made with the old method without cutting into the adjacent oven walls for supporting the timber or iron beams.

By the use of my novel method all brick work which can be left in an oven under repair is supported from the top, which leaves all the room available for the workmen. No large holes have to be cut to support the roof or parts of the wall not requiring repairs, nor is it necessary to leave large holes in the half-finished structure. Splitting of shapes is unnecessary. The floor is accessible at any place and may be repaired without cutting holes into the walls. The workman has the entire space of the oven available for performing his duties. It is not necessary with this method to wait until the heat of a defective wall is reduced to permit workmen to enter the oven before supports can be inserted, but this can be done while the oven is yet under considerable heat, and with the new method the shrinkage taking place during the process of cooling can be duly followed up and shrinkage cracks to some extent prevented by taking up the supports by means of screws or wedges.

The method and apparatus will be better understood by reference to the accompanying drawings, wherein—

Figure 1 is a transverse section through a plurality of by-product coke ovens, the walls constituting a combustion chamber of a pair of ovens having been burned out or removed and the roof of which is supported in the novel manner hereinafter described;

Fig. 2 is a view at right angles to that of Fig. 1;

Figs. 3 and 4 are detail views somewhat enlarged and corresponding to the elements shown in Figs. 1 and 2, and

Fig. 5 is a view similar to Fig. 3, showing a slight modification.

In the drawings, it will be seen that I have illustrated a fragment of a battery of coke ovens. In Fig. 1 the combustion chambers are indicated at 10, the coking chambers being indicated at 11, 12, 13 and 14. It will be noted that in Fig. 1 the walls composing the combustion chamber have been removed, either by accident or through deterioration. It, therefore, becomes nec-

sary to restore such walls or to lose the use of the two coking chambers 12, 13. These walls are re-built in the following manner: On suitable supports 15, at the top of the 5 furnace, is mounted a beam 16. This beam in the present instance is shown as composed of two angles placed back-to-back and serves to support a rod 17 through the medium of a large washer or plate 18 and a nut 19. 10 This rod projects downwardly through a sight opening 20, a plurality of which are provided in each combustion chamber throughout the length thereof. Plates 21 are located to underlie the brickwork 22, 15 composing the upper portion of the combustion chamber walls, one plate being placed on each side of the rod 17. A key 23 underlies the plates 21 this key passing through a suitable opening in the lower end 20 of the rod 17. It will be seen that this arrangement may be installed while the furnace is still quite warm. As shown in Fig. 2, the plates 21 may extend for a considerable distance underneath the brickwork if 25 desired, the distance which the plates extend being governed by their ability to support the brickwork without bending. It will be understood, of course, that a plurality of these rods are provided where the 30 entire wall is to be re-built. The nut on the upper end of the rod serves to exert the proper force and further enable the taking up of shrinkage as the wall cools. Of course, it will be understood that other expedients may be employed for taking up 35 this shrinkage.

In the construction of Fig. 5 the hanger rod is supplemented by a hook 24, which will be found to be useful in some instances.

40 The action in supporting the brickwork is of course the same as heretofore described.

The method of removing an oven wall for repair is accomplished in the following manner: Over the two ovens adjacent to the 45 ones under repair the supports are placed connected by the beam 16. From this beam a hanger 17 is suspended, the threaded upper end and the nut thereon serving to adjust the hanger primarily and to take up 50 shrinkage from cooling. The hanger is projected through an opening in the brick-work such as inspection or sight openings, charging holes, etc., the bottom of the hanger being provided with an eye or hook 55 as conditions may indicate to be the most suitable. If a hot oven is to be repaired, the bar or hanger may be formed by a jointed member which will fold alongside the hanger when passing through the hole,

and which will spread out and underlie the 60 brickwork when pulled into position. Ordinarily plates or straps 21 are located underneath the brickwork and are held in place by the key 23. The key can very readily be 65 inserted by the removal of but half a brick shape and on completion of repairs will not require a hole larger than one shape for removal. On the completion of the repairs one after another of the suspension hangers are withdrawn, leaving but a very small 70 opening to be filled while the roof is unsupported; in fact, this opening is only the size of one shape. In this manner the 75 repairs can be made with the same allowances for joints as are contained in the original work and without cutting the shapes to fill in holes where supports were used other than as herein described.

It is obvious, of course, that the method may be carried out by a mechanism other 80 than herein disclosed and I do not therefore wish to be limited to the apparatus or the exact steps herein referred to.

I claim:

1. The method of repairing an injured or 85 defective wall of a by-product coke oven having vertical openings through the roof leading to combustion chambers in the walls which consists in supporting a beam above the roof of the furnace and upon the two 90 walls adjacent to the one to be repaired, suspending a supporting member through one of the aforesaid openings in the roof, supporting the roof from the lower end of said supporting member and then repairing the 95 wall as required and removing said supporting member.

2. The method of repairing an injured or 100 defective wall of a by-product coke oven having vertical openings through the roof leading to combustion chambers in the walls which consists in supporting a beam above the roof of the furnace and upon the two 105 walls adjacent to the one to be repaired, suspending a supporting member through one of the aforesaid openings in the roof, to an opening beneath the top of the combustion chamber in the wall to be repaired, supporting said top of the combustion chamber by said supporting member, repairing 110 the desired wall and removing said supporting member.

Signed at Fairfield, Ala., this 25th day of Apl. 1916.

ALBERT H. CHALMERS.
